[57] **CLAIM**

The ornamental design for a latch for rolling gates, as shown and described.

DESCRIPTION

FIG. 1 is a top, front, and left side perspective view of a latch for rolling gates showing my new design; FIG. 2 is a bottom, rear, and right side perspective view thereof;

FIG. 3 is a rear elevational view thereof;

FIG. 4 is a top, front, and left side perspective view of an alternate embodiment thereof;

FIG. 5 is a bottom, rear, and right side perspective view of the embodiment of FIG. 4; and

FIG. 6 is a rear elevational view of the embodiment of FIG. 4.

The broken-line disclosure of a fragment of a rolling gate assembly in the views is for illustrative purposes only and forms no part of the claimed design.
